DESIGN FOR A SUPPORT FOR VASES OR OTHER ARTICLES.

SPECIFICATION forming part of Design No. 13,980, dated June 12, 1883.

Application filed September 26, 1882. Term of patent 7 years.

UNITED STATES PATENT OFFICE.

FREDERICK RATCLIFF, OF NEW BEDFORD, MASSACHUSETTS.

DESIGN FOR A SUPPORT FOR VASES OR OTHER ARTICLES.

SPECIFICATION forming part of Design No. 13,980, dated June 12, 1883.

Application filed September 26, 1882. Term of patent 7 years.

To all whom it may concern:

Be it known that I, FREDERICK RATCLIFF, of New Bedford, in the State of Massachusetts, have invented certain new and useful Improvements in Supports for Vases and other Articles; and I do hereby declare the following to be a full, clear, and exact description of the invention, such as will enable others skilled in the art to which it pertains to make and use it, reference being had to the accompanying drawing, which forms part of this specification.

My invention relates to an improvement in supports for vases and other articles; and it consists in a unique and ornamental design consisting of an elephant in a sitting attitude, as will be more fully described hereinafter.

The accompanying figure illustrates my invention.

A represents an elephant in a sitting attitude, having the two front legs, C, extended as shown, and having the trunk D coiled into a ring, so as to form a holder for a vase, card-receiver, pin-cushion stand, bell-holder, and

many other such articles. Any article which is to be supported by this figure of the elephant, which may be made of any desired size and of any material that may be preferred, must have a shank or extension which will pass down through the ring that is formed by the trunk, as shown. This figure of the elephant may either be attached to a suitable base, or the lower portion of the body will be made sufficiently square to form a base.

Having thus described my invention, I claim—

As a design for a holder for various articles, the figure of an elephant in a sitting attitude, the trunk being formed into a circle, as shown and described.

In testimony whereof I affix my signature in presence of two witnesses.

FREDERICK RATCLIFF.

Witnesses:

CHAS. F. SWIFT,
FREDK. S. SHIRLEY.
